UNITED STATES PATENT OFFICE.

THOMAS B. DOOLEY, OF MALDEN, MASSACHUSETTS, ASSIGNOR TO
JOSEPH MIDDLEBY, JR., OF MALDEN, MASSACHUSETTS.

PRINTING-PRESS.

No. 811,488.

Specification of Letters Patent.

Patented Jan. 30, 1906.

Application filed April 10, 1903. Serial No. 151,974.

To all whom it may concern:

Be it known that I, THOMAS B. DOOLEY, a citizen of the United States, and a resident of Malden, in the county of Middlesex and State 5 of Massachusetts, have invented certain new and useful Improvements in Printing-Presses, of which the following is a specification.

My improvements are herein shown and described as applied to a platen-press of the 10 jobbing type, to which type of press the main features of my invention are particularly applicable and include a novel platen and mechanism for operating the same, an adjusting throw-off, and certain other features herein 15 after described, the principal object of my invention being to provide a high-speed press of the type referred to which shall be simpler and more compact in construction, as well as lighter and easier to run than prior presses of 20 this type.

The inking mechanism which is herein shown and described in combination with the features above referred to for the purpose of showing a complete and operative press is 25 not herein claimed, being described and claimed in a divisional application filed by me on the 16th day of September, 1903, Serial No. 173,406.

My improvements in their preferred form 30 are illustrated in the accompanying drawings, in which—

Figure 1 is an end elevation of a jobbing-press containing said improvements with a portion of one of its gears broken away. Fig. 35 2 is a top plan view of the press with portions of the inking-rollers and inking-table broken-away. Fig. 3 is a vertical transverse section taken on the line 3 3 of Fig. 2. Fig. 4 is a vertical longitudinal section through the 40 press looking toward the rear thereof, the plane of section being indicated by the line 4 4 in Fig. 3. Fig. 5 is a vertical transverse section through the ink-distributing table, showing also the adjacent parts by means of 45 which it is operated. Fig. 6 is a fragmentary elevation of a portion of a shaft which operates the ink-distributing table. Fig. 7 is a side elevation, on an enlarged scale, showing one of the guides for the platen-carrier. Fig. 50 8 is a side elevation of one of the plates which carries the type-bed. Fig. 9 is a perspective view illustrating a portion of the platen and platen-carrier. Fig. 10 is a section detail 55 illustrating an adjustment of the platen-car-

rier. Fig. 11 is a detail perspective view of 55 my throw-off, hereinafter described.

The framework of the press shown in the drawings comprises two end portions or uprights 2 2, which carry the working parts of the press and are connected by suitable tie-rods 3 and by said working parts. My press may be driven by any suitable means, but is herein illustrated as a foot-power press, being provided with a treadle 4, connected by a rod 5 with a crank 6, interposed in the transversely-extending shaft 7, the latter being journaled in the uprights 2 2 and suitably connected by gears or otherwise with the other working parts.

On the inner side of each of the uprights 2 2 is secured a supplementary supporting-plate 8, the shape of which is shown in detail in Fig. 8, said plates 8 8 being spaced away from the uprights 2 2 for a purpose hereinafter described. Each plate 8 is preferably 75 provided with a hub 9, cast integral therewith and adapted to pass through and fit a socket 10, formed in the corresponding upright 2, the plate 8 being bolted to said upright by bolts located adjacent to said hub, 80 as indicated in Fig. 8. The result of this construction is that the plates 8 are supported at and near their central portions only, and in order to provide the desired space between each plate 8 and the adjacent upright 2 the 85 walls of the corresponding socket 10 are extended inward or toward the plate 8 a short distance and engage a stop-face formed at the base of the hub 9, as best shown in Fig. 4. The front edges of the plates 8 8 are joined by 90 a strong vertical cross-plate 11, which serves as the type-bed and is adapted to receive and hold a form of type on its front face in any suitable manner.

Within the space left between each plate 8 95 and the adjacent upright 2 is located a pair of sprocket-wheels 12 and 13, one such pair of sprockets being thus provided at each end of the press. The upper sprockets 12 are journaled on studs 14, carried by the corresponding uprights 2, and the lower sprockets 13 are keyed to a transversely-extending shaft 15, journaled in one of the uprights 2 and in a bearing 16, secured to the opposite plate 8. This shaft 15 is provided on its outer end 100 with a gear 17, meshing with a gear 18, secured to the driving-shaft 7. Around each pair of sprockets passes a sprocket-chain 19, which

carries a suitable number of inking-rollers 20, four of such rollers being shown in the drawings.

Between the upper and lower pairs of the 5 sprocket-wheels and at the rear of the machine is located a vertical ink-distributing table in such position that the travel of said sprocket-chain will carry the inking-rollers 20 over said inking-table in contact with its rear or 10 outer surface. Briefly described, this ink-distributing table which is claimed in my divisional application above referred to consists of a stationary vertical frame 25, secured at its ends to the rear edges of the plates 8 and provided with a number of parallel horizontal 15 slots 26, in each of which a plate 27 is mounted to slide lengthwise of the slot—that is to say, transversely of the machine. The outer faces of these plates are flush with the outer face of 20 the frame 25, and the plates 27 are kept from falling laterally out of said frame, as by making the adjacent edges of said plates and the slots 26 V-shaped, so that one fits within the other and slides therein. The distributing of 25 the ink is accomplished by reciprocating the plates 27 in an endwise direction, to which end each of said plates is provided with a rack 28, meshing with a pinion 29, secured to the frame 25, each pinion meshing with the racks 30 on two of the plates, so that by the reciprocation of either plate 27 the adjacent plate or plates will be moved correspondingly, but in the opposite direction. One of the plates 27 is positively reciprocated by means of a shaft 35 30, having a cam-groove 31 cut in its surface, in which groove is located a traveler 32, secured to said plate 27. The cam-groove 31 is composed on one side of the shaft 30 of two inclined portions, which cross each other, and 40 on the other side of said shaft the adjacent ends of these inclined portions are connected by circumferential portions, as best shown in Fig. 6, so that the traveler 32 dwells momentarily at the limit of its movement in either 45 direction. As shown in Fig. 5, the traveler 32 is composed of a stem 33, mounted to turn in a boss 34, secured to the middle plate 27, and 35 is a finger secured to said stem and having its free end fitted to travel in the cam-groove 31. 36 is a stop-screw threaded into 50 the boss 34 and adapted to hold the traveler in place in the cam-groove. It is to be understood that any other suitable inking mechanism may be used in connection with the 55 remaining features of my press. The shaft 30 may also serve to operate the platen, as herein-after described, and to this end is journaled in the hubs 9, formed on the plates 8, and extends through said hubs at each end of the 60 machine, at one of which ends it is provided with means whereby it may be rotated, such as a gear 37, connected by gears 38 and 39 with a pinion secured to the main driving-shaft 7. This arrangement for journaling said shaft 30 65 forms one of the features of my construction,

as it provides a suitable bearing for said shaft without making it necessary to form journal-boxes in the uprights 22 and at the same time increases the strength and stability of the parts of the machine.

The platen on which the sheets to be printed are placed and carried to the type preferably comprises a shell 40, having its face recessed to receive the plate or platen proper, 41, which is held therein by a screw-bolt 42, Fig. 3, and is justified by means of four bolts 43, bearing on said platen proper, 41, near its corners. It is customary to cover the working face of the platen with a sheet of heavy paper, and to this end the edges of the plate 41 may be recessed, as at 44, Fig. 9, to receive a frame 45, the sheet of paper (not shown) being secured to the plate by removing the frame 45, laying the sheet on the plate with its edges projecting over the recessed portion 44, and then 80 forcing said frame into place, thereby turning the edges of the sheet downward and clamping them between said frame and plate. The shell 40 is provided with strong laterally-extending hubs 46, Fig. 2, which project over 90 horizontal forwardly-extending portions 47 of the uprights 22, and a rod 48 passes through said hubs and projects therefrom at each end of the machine. There is also secured to each of said hubs an arm 49, Fig. 7, 95 having its outer or free end provided with a slot 50, extending substantially at right angles to the working face of the platen and containing a block 51, which is arranged to slide therein, and is pressed toward the outer end 100 of said slot by a spring 52. Each block 51 is perforated to receive and turn on the end of a fixed pin 53, secured to the corresponding upright 2, and each end of the rod 48 is connected by a rod 54 with reciprocating means, 105 such as crank-pins 55, carried, respectively, by the gear 37, and by a corresponding wheel 56, secured to the other end of the shaft 30. 57 represents springs extending from the lower portion of the shell 40 to convenient fixed 110 points on the framework of the machine and normally in a state of compression, so that they tend to force the platen upward. The platen is also provided with fingers or grippers 58 for holding the sheets to be printed against its 115 working face. These fingers may be of any usual construction and are not specifically described herein, as they form no part of my invention.

The parts just described are proportioned 120 and arranged to operate as follows: Starting from the position shown in Fig. 1, it will be seen that when in this position the platen has its working face uppermost and nearly horizontal, in convenient position to receive a 125 sheet to be printed. Assuming that such a sheet has been placed upon it and that the shaft 30 is then rotated, the first result of such rotation is to draw the rod 48, and with it the shell 40 and platen proper, 41, toward 130

the type-bed, said platen and connected parts turning on the pins 53 as an axis and being supported by the springs 52 and also to an increasing extent by the springs 57. This 5 turning of the shell 40 continues until its hubs 46 come in contact with the flat guiding-surfaces formed by the upper edges of the portions 47 of the uprights 2 2, the springs 57 acting as a cushion and preventing any shock 10 or jar. As soon as said hubs have come in contact with said guiding-surfaces the latter and the sides of the slots 50 form parallel guides, which hold the platen with its working face vertical and permit a sliding movement 15 thereof toward the type-bed, which movement is produced by a continued rotation of the shaft 30 until the sheet to be printed is brought against the type and the impression is taken. This position is shown 20 in Fig. 3 and corresponds to that position of the shaft 30 in which the pins 55 are in their extreme right-hand position. The reverse movement of the platen then commences as the shaft 30 continues to rotate, the first re- 25 sult of such movement being to push the platen horizontally away from the type-bed until adjustable bolts 59, carried by the arms 49, come in contact with the ends of the blocks 51, whereupon the shell 40 and con- 30 nected parts turn on the pins 53 as an axis and are lifted from the guiding-surfaces 47 and brought back to the position shown in Fig. 1, with the working surface of the platen in convenient position for the removal of the 35 printed sheet and the substitution of an un- printed one. It will be understood that during these movements the sprocket-chains 19, carrying the inking-rollers 20, are driven continuously and the driving-gears are so pro- 40 portioned that said rollers pass once around the sprocket-wheels during each cycle of operations of the platen. The inking-rollers are also so located on the sprocket-chains that they pass over the form of type just be- 45 fore an impression is taken. When the platen is drawn toward the type-form, just before it reaches the latter the inking-rollers pass over the type, and while the platen is re- 50 turning to the position shown in Fig. 1 the inking-rollers pass over the distributing-table. The shape of the cam-groove 31 is such that it takes two rotations of the shaft 30 to give the plates 27 a complete reciproca- 55 tion in both directions, and the straight or circumferential portions of said slot 31 are so located that said plates 27 are stationary at the times when the inking-rollers are passing over them, the distribution of the ink being thus accomplished in an obvious manner. 60 It will be seen that my construction pro- 65 vides for a strictly parallel movement of the platen toward and from the type just before and after the impression, that all the move- ments of the platen are confined to a small space and produced by simple means, and

that the platen when receiving a sheet has its working face in a most convenient and accessible position for this purpose.

It is desirable to provide for a dwell of the platen while the printed sheet is being re- 70 moved and replaced, and to this end I prefer to operate said platen through a pair of self-locking mutilated gears, the gears 37 and 38 being shown as of this construction and the desired dwell being provided for by omitting 75 a sufficient number of teeth from the gear 38, so that no movement of the gear 37 can occur during this portion of the rotation of said gear 38.

In order to prevent any possibility of blurring the impressions, I prefer to provide locking devices consisting of plates 59^a, one at each end of the machine, which plates may be cast in one piece with the uprights 2, re- 80 spectively, and are each provided with a 85 notch 60, adapted to receive and fit the edge of a rib or flange 61, cast on the shell 40, one at each end thereof. When the platen is moved toward the type-bed, the flanges 61 enter the notches 60 and are held thereby at 90 the instant when the impression is taken against any vertical movement in either di- 95 rection, thus preventing any possible lateral slip of the platen with respect to the face of the type.

It will be seen by referring to Figs. 10 and 2 that the side edges 62 of the shell 40 are flush with the plane of the working surface of the platen proper, 41, and that the side edges 63 of the cross-plate 11, which holds the form 100 of type, are also substantially flush with the level of the surface of the type, so that, as shown in Fig. 2, when the impression is being taken the side edges of the platen and the plate 11 are in contact with each other, or 105 practically so, and thus act as a stop to limit the depth of the impression taken from the type. This arrangement is important and useful where the type-form contains but few 110 type, in which case it has been found in the use of prior presses that the type is apt to cut the sheet or to give too deep an impression. With my construction the platen may be so 115 adjusted that the depth of the impression can never be excessive, regardless of the number of type being printed from. For adjusting the platen as just described I prefer to make the rod 48 capable of turning in the hubs 46 as bearings, and I provide it at each end with an eccentric pin 64, which carries the corre- 120 sponding rod 54, as shown in Fig. 10. As thus constructed the hubs 46 and connected parts may be adjusted with respect to the rods 54 by turning the rod 48 with respect to said hubs, thus providing for the desired adjust- 125 ment of the platen with respect to the type- bed. It will be evident that by turning the rod 48 in a direction to move the platen away from the type-bed the effect of a throw-off 130 will be obtained, and for utilizing this feature

as a throw-off and also for adjusting the platen with delicacy I have shown in Figs. 2 and 11 an arm 65, rigidly secured to the extended outer end of one of the pins 64 and provided 5 with a pivoted locking-finger 66, having an operating-handle 67 and adapted to enter a notch 68 in a ring 69, which ring is mounted to turn on the corresponding hub 46 and is locked in any desired position on said hub by 10 means of a set-screw 70 passing through a circumferential slot in said ring. By turning the rod 48 the platen is accurately adjusted to the proper position with respect to the type-bed, and the ring 69 is then adjusted to 15 such position that the locking-finger 66 will enter the notch in said ring, which ring is then firmly clamped to the hub 46 by its set-screw 70. The handle 67 may now be utilized as a throw-off by disengaging its locking-finger 20 66 from the notch 68, and the parts may be quickly and easily restored to the position of proper adjustment by moving said handle until said locking-finger 66 is again in position to enter the notch 68. The handle 67 is shown 25 as provided with a stop-finger 71, which limits its pivotal movement and enables the arm 65 to be readily operated thereby.

The various features of my invention, although particularly adapted and intended to 30 be used in combination, may be used independently of one another to a certain extent and may be variously modified without departing from my invention, as will be evident.

I claim—

35 1. In a printing-press, the combination of a platen-carrier, parallel guides therefor, extending at right angles to its working face, pivots coöperating with said guides and providing stops to limit the rearward movement 40 of the carrier, and means for reciprocating said carrier on its guides and turning it in an arc of a circle having said pivots as a fixed central axis.

45 2. In a printing-press, the combination of a platen-carrier, parallel guides therefor, extending at right angles to its working face, pivots coöperating with said guides and providing stops to limit the rearward movement 50 of the carrier, springs interposed between the pivots and the ends of the corresponding guides for cushioning the carrier, and means for reciprocating said carrier on its guides and turning it on said pivots as a central axis.

55 3. In a printing-press, the combination of a platen-carrier having slotted arms forming guides, relatively fixed pivotal devices arranged to slide in the slots of said arms respectively and providing stops to limit the rearward movement of the carrier, supplementary guides for said carrier arranged to operate in parallelism with said slots, and means for reciprocating said carrier on the latter guides and for turning it in an arc of a circle having said pivotal devices as a central axis.

65 4. In a printing-press, the combination of a

70 platen-carrier and guides on which said carrier is adapted to slide at right angles to its working face, arms secured to said carrier and provided respectively with slots, blocks mounted to slide in said slots and journaled 75 on fixed pivots respectively, said blocks forming stops to limit the rearward sliding movement of the carrier, and means for reciprocating said carrier on said guides and for turning it on said pivots as a central axis. 75

5. In a printing-press, the combination of a platen-carrier and guides on which said carrier is adapted to slide at right angles to its working face, arms secured to said carrier and provided respectively with slots, blocks 80 mounted to slide in said slots and journaled on fixed pivots respectively, said blocks forming stops to limit the rearward sliding movement of the carrier, a spring interposed between each block and the forward end of the 85 corresponding slot, and means for reciprocating the carrier and for turning it on said pivots as a central axis.

6. In a printing-press, the combination with a type-bed having forwardly-turned 90 edges, of a platen-carrier movable toward and from the type-bed and having edges adapted to abut against the edges of the type-bed when in the impression position, a platen carried by said carrier and means for 95 adjusting said platen.

7. In a printing-press, the combination with a type-bed having forwardly-turned edges, of a platen-carrier movable toward 100 and from the type-bed and having edges adapted to abut against the edges of the type-bed when in the impression position, a platen carried by said carrier, a rod or shaft journaled in said carrier and provided at its 105 ends with eccentrically-mounted pins, and means connected to said pins for reciprocating said carrier.

8. In a printing-press, the combination with a type-bed having forwardly-turned 110 edges, of a platen-carrier movable toward and from the bed and having edges adapted to abut against the edges of the type-bed when in the impression position, a platen carried by said carrier, a rod or shaft journaled in said carrier and provided at its ends with 115 eccentrically-mounted pins, means connected to said pins for reciprocating said carrier, and a throw-off lever connected to one of said pins.

9. In a printing-press, the combination of a 120 platen-carrier, a rod journaled therein, means connected eccentrically to said rod for operating the carrier, an arm rigidly connected to said rod and having an operating-handle pivoted thereto, said handle being provided with 125 a locking-finger, and a ring adjustably mounted on said carrier and provided with a notch adapted to receive said locking-finger.

10. In a printing-press, the combination of a 130 platen-carrier, a rod journaled therein and

provided at its ends with eccentrically-mounted pins, means connected to said pins for reciprocating said carrier, a ring adjustably mounted on said carrier and provided with a notch, and a lever connected to the said rod and provided with a locking-finger adapted to engage said notch.

11. In a printing-press, the combination of a platen-carrier and guides therefor, said guides permitting a sliding movement of the carrier toward and from the type-bed, pivots coöperating with said guides and providing stops to limit the rearward movement of the carrier, and means for reciprocating said carrier on its guides and turning it on said pivots as a central axis, said means comprising a pair of intermittent self-locking gears, means for driving one of them, and crank-rods connecting the driven gear with the platen-carrier.

12. In a printing-press, the combination with a platen-carrier and guides therefor, of pivots coöperating with said guides and providing for a turning movement of said car-

rier, springs 52 interposed between said pivots and one end of the guides, and means for operating the carrier.

13. In a printing-press, the combination of a platen-carrier mounted to slide toward and from the type-bed and to turn on pivots at a distance from said type-bed, means for operating said carrier, and springs 57 for supporting the latter, substantially as described.

14. In a printing-press, the combination with a platen-carrier mounted to slide toward and from the type-bed and to turn face upward at a distance from said type-bed, of means for operating said carrier comprising intermittent self-locking gears and crank-rods connecting the driven gear with the carrier.

In testimony whereof I have hereunto subscribed my name this 7th day of April, 1903.

THOMAS B. DOOLEY.
